UNITED STATES PATENT OFFICE.

THOMAS V. ALLIS, DECEASED, LATE OF PITTSBURGH, PENNSYLVANIA, BY HANNORA
E. G. ALLIS, ADMINISTRATRIX, OF PITTSBURGH, PENNSYLVANIA.

METHOD OF AND FURNACE FOR HEAT-TREATING SHEET AND TIN-PLATE BARS.

1,417,012.

Specification of Letters Patent. Patented May 23, 1922.

Application filed April 10, 1920. Serial No. 372,981.

To all whom it may concern:

Be it known that THOMAS V. ALLIS, late a citizen of the United States, deceased, late of Pittsburgh, in the county of Allegheny 5 and State of Pennsylvania, invented certain new and useful Improvements in Methods of and Furnaces for Heat-Treating Sheet and Tin-Plate Bars, of which the following is a specification.

10 The present invention relates to the art of heat-treating sheet and tinplate bars, and bears a certain relation to an application for patent entitled "Method of heat-treating sheet and tin-plate bars," Serial Number 15 214,270 filed in the United States Patent Office January 29, 1918, Thomas V. Allis, inventor. Reference is made to the description therein as to certain features in this 20 art which relate to the advantages of piling and heat-treating bars in the central region of pair furnaces as being conducive to producing uniformly heated bars; and as to the desirability of having non-oxidized surfaces 25 on the bars preparatory to rolling the metal into sheets.

The present invention is illustrated in the accompanying drawings forming part of this specification, by its use in connection with a depressed temperature equalizing 30 bar-pit (of which two types of same are shown), where the sheet and tinplate bars are "soaked" in the central part of the furnace (where the said bar-pit is located on account of this region of the furnace having 35 the most constant and equable temperature), until all the bars are in a uniformly heated condition suitable for rolling down into sheets.

In the drawings; Figure 1 is a longitudinal central vertical section on line 1—1 of the pair furnace shown in Figure 4.

Figure 2 is a transverse vertical section on line 2—2 of Figure 4.

Figure 3 is a transverse vertical section 45 on line 3—3 of Figure 4.

Figure 4 is a horizontal section of the pair furnace shown in Figure 1, taken on line 4—4 of Figure 1.

Figure 5 is a transverse vertical section 50 of a modified form of hearth, for the furnace shown in Figure 4, taken on line 5—5 of Figure 6.

Figure 6 is a plan view of Figure 5.

The constructional features of the furnace shown in Figures 1 to 4 inclusive will 55

first be described. The numeral 1 indicates a pair furnace, having a heating chamber 2, and a bridge wall 3, pierced by a cut-away portion 4, having a preferably rounded top surface 5. The hearth 6 has formed 60 therein several depressions or pits 7, 8, 9 for purposes described below. The depression or bar-pit 8 has preferably a "saddle-back" or hip-shaped bottom 10 of metal or refractory material, adapted to support a series 65 of piled sheet or tinplate bars 11. The saddle-back 10 is beveled transversely as seen in Figure 2, and also sloped rearwardly toward the interior of the furnace as shown in Figure 1. The walls of the bar-pit 8, 70 being of refractory material are protected from the "wear" of the edges of the bars 11, by means of upright gage bars 12, 12 etc. which also hold the bars in vertical alignment, when stacked or "gaged" against 75 same. A metal cross-bar 13 extends across the bar-pit 8, for the purpose of holding the upright gage bars 14, 14 in position. It is seen that on account of the transverse bevel, and the rearward slope of the saddle- 80 back 10, that the metal bars range themselves practically automatically against the gage bars 12 and 14, gravity assisting in the operation of gaging the bars with their longitudinal and vertical edges (both on the 85 rear and on the side of the bars) in perfect alignment without any protruding edges or surfaces being exposed to the action of the furnace heat. The purpose of the even piling is to avoid uneven heating, or oxidized 90 surfaces as before mentioned herein. The depression 9 is a continuation of the bar-pit 8, but has its bottom surface preferably curved as shown in Figure 1 at 15. The underlying idea being that as the heated 95 gases come from fire-box 16, they pass over the fire-wall through the cut-away portion 4, strike against the roof and front wall of the furnace at points say 17, 18 approximately, and then deflect downwardly, passing through the depressions 8 and 9, and reverberate continuously, in the direction of an elongated ball or oval in direction between the fire wall and the front wall of the furnace, thus serving to give the bars 100 piled in the bar-pit 8 the benefit of this constantly maintained high and equable temperature, which tends to uniformly soak the bars and obtain a homogenous mass of heated material. As set forth in the before 110

mentioned application, Serial Number 214,270, when the bars are piled near the side walls 19 of the furnace 1, as in some types of furnaces, they become subject to 5 serious "wall drafts" due to the proximity of the brick walls, and other poorly understood but well-known causes, and hence the location of the soaking pit 8 is placed in the center of the furnace in the present invention, where a more even and constant 10 heat is maintained at all times, and where the bars 11 receive the reverberatory action of the burning gases as above described. The depression 7 is of substantially the same 15 width as pit 8, with a slightly flared mouth as seen in Figure 4, so that the bars 11 can be readily manipulated and withdrawn from the furnace.

On the hearth 6 are the skid castings 20, 20 which are adapted to support sheet and tinplate bars 21, 22 etc. in an inclined position resting on one edge and a side with their edges in approximately vertical and longitudinal alignment. It is seen that 25 gravity assists the bars 21, 22 etc., as in the case of the bars 11, to gage themselves against the faces 23, 23 etc. of the castings 20, 20. The furnace 1 is also provided with "down-take" flues 24, 25, connecting passages 26, 30 27, 28, and a stack flue 29 to carry off the waste gases of combustion in the usual fashion.

In the Figures 5 and 6 of the drawings, I have shown a modified form or type of 35 hearth which is adapted to displace the one shown in Figure 4, and in which it is seen from said Figures 5 and 6 that the hearth skid castings 20, 20 are replaced by 30, 30 which are similar, and the saddle-back 10 by the piling rack 31. The castings 30, 30 are placed on an inclined surface 34, while the rack 31 remains on a horizontal depressed surface in a transverse direction as seen in Figure 5. The piling rack 31 comprises a 40 vertically disposed member 32, and two oppositely projecting members 33, 33, as clearly illustrated in Figures 5 and 6, for piling the bars 35 with their longitudinal and vertical edges in alignment. The use of the 45 modified arrangement of hearth skids and piling rack will be described below.

In carrying out my invention in the first 50 described type of furnace, I proceed as follows. The bars are charged through the small doors 36, 37 etc., which expose only a 55 small portion of the opening 38 at any one time, so as not to disturb the heat conditions within the heating chamber 2 more than is absolutely necessary, the idea being to hold the "soaking" temperature of the bars within 60 the said chamber at a constant point as far as practicable. The bars charged are placed in piles illustrated by 21, and 22, etc. on the hearth skids 20, 20, two pairs of bars 65 usually being associated and handled as a

unit when placing them on the skids. After the bars are partially heated on the hearth skids, they are removed one or more pairs at a time, by lifting them manually with a pair of tongs inserted in the longitudinal 70 grooves 39 of the hearth skids, and placed on the saddle-back 10 in the bar-pit 8. In forming the piles on the saddle-back 10, an outer pile of bars 21, i. e. a pile nearer the doors 36, 37, etc., and inner pile 22, i. e. 75 a pile nearer the fire wall 3, are successively superimposed upon each other in alternate relation on the saddle-back. The reason for this procedure is that the inner piles of bars 22 positioned on the skids 20, in the 80 interior of the heating chamber 2, are exposed to a more intense heat than the outer piles 21, and when they are piled alternately on the saddle-back 10, the temperature of the whole mass of bars is equalized. The 85 hotter bars radiate the heat to those of lower temperature, and the latter readily absorb the heat so radiated according to a well understood physical principle, and thus a mass of bars of a uniform caloric condition is 90 produced. Further it is seen that the even piling of the bars 11, on the saddle-back 10 with their longitudinal, side and end edges in perfect alignment prevents all oxidation of the surfaces of the bars and undesirable 95 "scale" is reduced to a negligible minimum. After the bars have been "soaked" or treated sufficiently in the bar-pit 8, they are withdrawn as needed through doors 36, 37 and reduced by rolling in a mill into sheets of 100 the proper gage.

The method adopted with the type of furnace shown in Figures 5 and 6 is substantially the same as that just described, but it is evident that the transference of bars from the skids 30 to the piling rack 31 is accomplished much easier than the first described method, due to the relative nearness of the bars in the two positions, i. e. on the skids 20, and on the piling rack 31. 110

What I claim is:

1. The method of heating sheet and tinplate bars, which consists in piling them into a mass with their side, longitudinal and end edges in alignment, in the center of a 115 furnace hearth, and heat-treating said mass to obtain uniformly heated bars.

2. The method of heat-treating sheet and tinplate bars, which consists in piling them in a bar-pit in the center of a furnace, with 120 all their edges in substantial vertical and longitudinal alignment, and heat-treating the mass of bars while so positioned, to produce bars of a uniform caloric condition.

3. The method of heat-treating sheet and tinplate bars to uniformly soften and minimize their oxidation, which consists in initially heating them in primary piles on a furnace hearth, transferring and arranging said piles against a gage in a bar-pit formed 125 130

- below the general level of the furnace hearth, and then completing the heat-treatment while the bars are in said bar-pit.
4. The method of heat-treating sheet and tinplate bars which consists in initially heating them in primary piles, transferring and arranging said piles to form secondary piles in a centrally disposed bar-pit to form piles composed of alternate layers of bars taken from piles of varying comparative temperatures, and completing the heat-treatment while the bars are disposed in the said bar-pit with their vertical and longitudinal edges in alignment.
- 15 5. The method of heat-treating sheet and tinplate bars, which consists in initially heating them in primary piles, transferring and arranging said piles against a gaging means in a bar-pit, to form secondary piles composed of alternate layers of bars of different comparative temperatures, and then completing the heat-treatment while the bars remain in the secondary piles with their side, end and longitudinal edges in alignment.
- 25 6. A pair furnace hearth having a pair of horizontally disposed longitudinal portions for heating bars, and a longitudinal depressed bar-pit provided with means for aligning the longitudinal and end vertical edges of a pile of bars for homogeneously heat treating same.
- 35 7. A pair furnace hearth having means for heating sheet bars and a depressed bar-pit, provided with means for aligning the longitudinal, side and end edges of a pile of bars deposited therein for soaking purposes.
- 40 8. A pair furnace hearth having means for heating sheet bars and a depressed bar-pit provided with means for aligning the longitudinal and vertical edges of a pile of bars deposited therein for heat treating purposes.
- 45 9. A pair furnace hearth provided with a bar-pit, having a saddle-back bottom adapted to longitudinally and vertically align the edges of a pile of sheet bars deposited therein for uniformly heating said bars.
- 50 10. A pair furnace hearth provided with a bar pit, having a saddle-back bottom, and means for aligning the longitudinal, side and end edges of a pile of bars deposited therein for heat treating purposes.
- 55 11. A pair furnace hearth provided with a bar-pit having a transversely beveled and longitudinally sloped saddle-back bottom, and means for aligning the longitudinal, and vertical edges of a pile of bars deposited on said saddle back.
12. A pair furnace bar-pit having a transversely beveled and longitudinally sloped saddle-back bottom, and means for aligning the longitudinal, side and rear vertical edges of a pile of bars deposited therein.
13. A pair furnace bar-pit having a saddle-back bottom, and a plurality of gage bars in the sidewalls of said bar-pit, a cross bar extending across the bar-pit, and a number of gage-bars engaging the cross-bar and the bottom of the bar-pit for aligning the rear vertical edges of a pile of bars piled within the bar pit.
14. In a pair furnace having a hearth, a firewall provided with a centrally disposed cut-away portion, a longitudinal central bar-pit below the general level of the furnace hearth, and means in said bar-pit for gaging a pile of sheet bars with their edges in longitudinal and vertical alignment.
15. In a pair furnace, a fire wall having a centrally disposed cut-away portion, a pair of hearth skid castings, each adapted to hold a series of sheet bars with their longitudinal and vertical edges in alignment, a centrally positioned bar-pit between the hearth skid castings, and below the general level of the furnace hearth, provided with means for aligning the edges of a pile of sheet bars placed in the bar-pit.
16. In a pair furnace, a pair of hearth skid castings, and a bar-pit below the general level of the said castings, and provided with means for aligning a pile of bars with all their edges in vertical and longitudinal alignment.
17. The method of heat-treating sheet and tinplate bars, which consists in initially heating them in primary piles on the inclined sides of a furnace hearth, transferring and arranging said piles to form secondary piles in a centrally disposed bar-pit, between the said inclined sides of the furnace hearth, to form piles composed of alternate layers of bars taken from the initial piles of varying comparative temperatures; and completing the heat-treatment while the bars are disposed in the said bar-pit with their edges in substantial alignment.

In testimony whereof I affix my signature.
